UNITED STATES PATENT OFFICE

2,627,559

SEQUENTIAL SWITCH

Philip C. Netzel, Philadelphia, Pa., assignor to
 General Electric Company, a corporation of
 New York

Application December 27, 1948, Serial No. 67,476

9 Claims. (Cl. 200—5)

1

The invention relates to sequential switches, particularly field discharge switches that are closed when the main field switches are opened and vice versa.

One object is to provide an improved form of sequential switch motion converting mechanism capable of converting the closing and opening movement for one pivotally mounted switch respectively into opening and closing movement for another coaxially pivotally mounted switch. This enables standard switch parts to be used in sequential switching service as, for example, field switching service where two standard switch units having a common reciprocating operating member may be spaced apart to constitute the main field switch with another standard discharge switch unit interposed therebetween to form a triple-pole field discharge type of breaker. In this way standard movable and cooperating switch contacts, as well as standard mounting bases, arc chutes, and a common reciprocating operating member can be employed for all poles.

Another object is to provide for overlapping the closing and opening of the sequential switches so that each switch is always closed before the other is opened. This feature is of importance where a field discharge breaker is used with synchronous machines to prevent excessive voltage being built up in the field winding in case the discharge resistor is disconnected therefrom while the field is open-circuited.

Other objects and advantages of the invention will appear in the following description of the accompanying drawings in which Fig. 1 is a perspective view of a triple-pole field discharge type circuit breaker embodying the reverse motion converting improvements of the present invention in a preferred form; Fig. 2 is an enlarged sectional view of the movable and cooperating switch contacts indicating the extended wiping action thereof that enables switch closing and opening overlapping to be obtained; Fig. 3 is a front view of the relatively stationary contacts shown in Fig. 2 indicating the standard multiple finger construction thereof; Fig. 4 is a side view partly in section of the intermediate field discharge unit of the triple-pole switch shown in Fig. 1 with the parts in the field discharge circuit closing position; Fig. 5 is a similar view with the field discharge switch unit in the open position; Fig. 6 is a partial front view of the field discharge switch motion converting mechanism shown in Figs. 4 and 5 more clearly illustrating the interrelation of the motion reversing parts; Fig. 7 is a schematic view of the 3-pole switch

2

shown in Fig. 1 with the field circuit and discharge connections thereto diagrammatically illustrated with the discharge circuit open and the field circuit closed; and Fig. 8 is a similar schematic view showing the intermediate field discharge switch in the closed position and the two main field switches in the open position.

As shown in Fig. 1, the triple-pole field discharge type breaker indicated generally by the reference character 10 is provided with two outside multi-contact simultaneously operable switch units or poles 11 and 12 for closing and opening the main field circuit and an intermediate multi-contact reversely operable switch unit or pole 13 for reversely opening and closing the field discharge circuit. As shown, the switch unit 11 is of standard form having a movable insulating link 15 operating a plurality of movable contact fingers 16 into and out of wiping engagement with the cooperating contacts 17. The movable contact fingers 16 are pivotally mounted at their lower ends on a current conducting pivot pin (like pin 42 shown in Fig. 4) extending between the side walls of the molded base 18. The cooperating contacts 17 also are pivotally mounted as more clearly shown in the enlarged view of Fig. 2, each contact 17 being formed with a pivotal bearing projection 20 of substantially semi-cylindrical form for seating in the open groove 21 formed in the inside surface of the J-shaped conducting member 22 to provide extended pivotal movement of the cooperating contact finger 17 as indicated by the dotted lines in Fig. 2. Each cooperating contact 17 is biased into the path of its cooperating movable contact finger 16 by means of a pin 23 sliding in a suitable opening 24 formed in the conducting member 23 and biased into engagement with the finger 17 by a compression spring 25. In this same way, the several cooperating contacts 17 of each pole of the breaker 10 may be of the same standard form and mounted in coaxial pivotal alignment and biased into the path of the cooperating movable contacts 16, which in turn may be of a standard form, for extended wiping engagement therewith as indicated in Figs. 2 and 3.

The insulating multiple contact operating switch link 15 of unit 11 carries a cross shaft 27 that serves to close and open the switch contacts 16 upon opposite reciprocation thereof in the guide slots 26 formed in each of the side walls 31 and 32 of the operating mechanism indicated generally by the reference character 33. The cross shaft 27 also is connected through a

link 28 to a pin 29 for operating an indicating mechanism that shows the open and closed position of the main switch contacts of poles 11 and 12 through the window 30. In the preferred form of breaker shown in Fig. 1, the switch operating mechanism 33 is of the improved trip-free toggle latch type described and claimed in Patent 2,549,441, filed by John A. Favre on September 23, 1947 and assigned to the present assignee, although it should be understood that the improved motion converting mechanism of the present invention may be used with other suitable forms of switch operating mechanism and switches if desired.

In the form of switch shown, the operating rod 15 27 is reciprocated inwardly in the slot 26 by a trip-free toggle latch mechanism so as to close the switch upon turning the operating handle 35 a quarter turn to the left from the vertical position in which it is shown and is released for 20 opposite reciprocation to the switch opening position to which it is biased as shown in Fig. 1 upon operation of the latch trip button 36. The operating handle 35 is rotatably mounted in the escutcheon plate 37 that is secured to the two side 25 plates 31 and 32 by the mounting screws 38 and the side plates 31 and 32 in turn are secured to the switch units 11, 12, and 13 by suitable mounting screws 39.

The reciprocating operating rod 20 27 spans the intermediate pole 13 and extends through a guide slot in the side wall 32 similar to the slot 26 and is connected to operate the movable contact fingers of the switch unit 12 by a link similar to the link 15 so that both of the main field switch units 11 and 12 are closed and opened simultaneously upon operation of the closing handle 35 and the opening trip button 36.

The intermediate discharge switch unit 13 is reversely opened and closed upon simultaneous closure and opening of the two outside main field switch units 11 and 12 and the improved reciprocating to reverse rotary motion converting mechanism for accomplishing this result is shown in Figs. 4, 5, and 6. As shown in Fig. 4, the movable switch member 16 and the cooperating switch member 17 of the intermediate discharge switch unit 13 are of the same standard form employed in the main field switch units 11 and 12 and this is also true of the parts that pivotally support and bias the cooperating contacts 17 in the manner previously described in connection with Fig. 2.

The movable switch contacts 16 of the discharge switch unit 13 are mounted in a contact carrier 41 that is rotatably mounted along with contacts 16 on pivot pin 42 that extends between the sides of the molded base 18 of the intermediate switch unit 13 coaxially with the pivoted contact fingers 16 for each outside pole 11 and 12. In each pole, the standard contact fingers 16 may be biased into good electrical contact with the current conducting pivot pin 42 by means of a leaf spring 43 and thus removably mounted upon the pin 42 so as to permit ready renewal of any movable contact finger that may deteriorate in service due to arcing or burning.

As shown in Fig. 4, the contacts 16 and 17 of the intermediate discharge switch unit are closed into wiping engagement by means of a toggle formed by the link 44 that is pivotally connected with the pin 45 mounted upon and extending from the contact carrier 41 and the double link 46 that is pivotally mounted upon the fixed pin 47 and connected with link 44 by means of pin

48. The toggle formed by the links 44-46 is biased to its extended position in which it is shown in Fig. 4 by means of a pair of tension biasing springs 49 and is collapsed to open the switch as shown in Fig. 5 by means of a lever 50 that is centrally pivoted on the fixed pivot pin 51 and has a cam motion sliding operating connection 52 formed by slot 54 at one end thereof with the toggle link 46 and also a lost motion sliding connection with the reciprocating switch operating rod 27 formed by the enlarged opening 56 at the other end thereof.

As shown more clearly in the partial end view of Fig. 6, the double pivot link 46 has its two spaced-apart halves on opposite sides of the centrally pivoted lever 50 that is provided with an enlarged opening 53 for permitting the fixed pivot pin 47 of the double toggle link 46 to extend through the lever 50 without interfering with the pivotal movement thereof. The lower end of the lever 50 is provided with the slot 54 for receiving therein an eccentric 55 that is adjustably clamped between the two halves of the toggle link 46 so as to form an adjustable sliding cam motion operating connection between the fixedly pivoted toggle 46 and the fixedly pivoted lever 50. The fixed pivot pin 47 for the double toggle link 46 is mounted in the side walls 57-58 of the U-shaped bracket 59 that is secured to the base 18 by suitable holding-down bolts 60. The fixed pivot pin 51 of lever 50 is similarly mounted between the side walls of the mounting bracket 59 and the two biasing springs 49 each have one end thereof engaging with a pin 61 that also extends between the side walls of the bracket 59 and the other ends of the springs are hooked around the bolt 63 that serves adjustably to clamp the eccentric 55 between the halves of the double toggle lever 46. The two centering bushings 64 serve to maintain the double toggle link 46 as well as the lever 50 in their properly aligned operating positions between the walls 57-58 of the mounting bracket 59.

Operation

As schematically shown in Fig. 7, the two outside poles 11 and 12 of the triple-pole field switch 10 when closed serve to interconnect the field winding 65 to be energized from suitable supply lines L1, L2, the energizing circuit extending from supply line L1 through conductor 66, pole 11, conductor 67, field winding 65, conductor 68, pole 12, and conductor 69 to the other supply line L2. As previously indicated, the poles 11 and 12 are closed by rotating the handle 35 a quarter turn to the left so as to reciprocate operating member 27 in the guide slots and thereby exert a force through the links 15 to operate the movable switch contacts 16 into wiping engagement with the cooperating switch contacts 17. During the pivotal movement of the movable switch contacts into initial engagement with the cooperating contacts, the reciprocating rod 27 moves across the enlarged lost motion opening 56 to take up the lost motion and thereafter rotates the lever 50 about its fixed pivot 51 in a clockwise direction and thereby through the cam motion sliding connection 52 provided by slot 54 effects a corresponding clockwise rotation of the toggle link 46 so as to quickly collapse the toggle and open the intermediate pole of the switch 13 during the wiping engagement of the two outside poles 11 and 12. As a result, the circuit through the field discharge resistor 71 is opened by the intermediate pole 13 only after

the energizing circuit for the field winding 65 is closed by the outside poles 11 and 12.

When the breaker 10 is tripped by operation of the latch trip push button 36 so as to open the outside poles 11 and 12 as shown in Fig. 8, the reciprocating rod 27 will move quickly in the opposite direction in the guide slots 38 and the two springs 49 will cause the lever 50 to immediately follow the motion of the reciprocating rod 29 so as to reset the toggle formed by the links 46 and 44 and thereby reclose the intermediate pole 13 as indicated in Fig. 8 before the contacts of the two outside poles 11 and 12 are moved out of wiping engagement. In this way, the extended wipe provided for the outside poles 11 and 12 insures that the intermediate pole 13 is closed to connect the discharge resistor 71 across the field winding 65 before the opening of the outside poles 11 and 12 can be effected.

What I claim as new and desire to secure by Letters Patent of the United States is:

1. A sequential switch mechanism having in combination a pair of coaxially pivoted separately operable switches, each having an operating link pivotally connected thereto, and sequential operating means therefor including a reciprocating operating member pivotally connected to one of the links for closing and opening the corresponding one of the switches and having independently pivoted double lever reverse rotary motion converting connections with the other link for reversely opening and closing the other switch upon opposite reciprocation of the operating member.

2. A sequential switch mechanism having in combination a pair of coaxially pivoted separately operable switches, each having an operating link pivotally connected thereto, and sequential operating means therefor including an operating rod slidably mounted for lateral reciprocation and having a pivotal connection with one link for closing and opening the corresponding one of the switches and an independently pivoted double lever reverse rotary motion converting toggle linkage connection with the other link for reversely opening and closing the other switch upon opposite reciprocation of the operating rod.

3. A sequential switch mechanism having in combination a pivotally mounted switch having a coaxially pivotally mounted switch in alignment on each side thereof and sequential operating means for said switches including a laterally reciprocable operating rod spanning the intermediate pivotally mounted switch and having a separate link connection for closing and opening each of the coaxially pivoted outside switches simultaneously and having a reciprocating to reverse rotary motion converting toggle linkage connection for reversely opening and closing the intermediate pivotally mounted switch upon opposite reciprocation of said operating rod.

4. A sequential switch mechanism having in combination a pair of separately operable switches, means including a movable operating member having connections for closing and opening one of the switches upon opposite movements of the member, means including a toggle having a biasing spring for normally extending the toggle to close the other switch and a centrally pivoted lever having one end provided with a cam motion connection with one of the toggle links and the other end provided with a lost motion connection with the movable member for collapsing the toggle to open the other switch when the one switch is closed.

5. A sequential switch mechanism having in combination a pair of aligned separately operable switch members, each having an operating link pivotally connected thereto and each having a movably mounted cooperating contact biased for wiping engagement and disengagement therewith, sequential operating means including a reciprocating operating member having a pivotal connection with one link for effecting wiping engagement and disengagement of the corresponding one of the switch members with its cooperating contact upon opposite reciprocation of the operating member and having independently pivoted double lever motion reversing connections with the other link for reversely effecting wiping disengagement and engagement of the other switch member with its cooperating contact during the opposite wiping operations of the one switch member.

6. A sequential switch mechanism having in combination a pair of coaxially pivoted separately operable switch members, each having an operating link pivotally connected thereto and each having a movably mounted cooperating contact biased for wiping engagement and disengagement therewith, and sequential operating means including a reciprocating operating member having a pivotal connection with one link for effecting wiping engagement and disengagement of the corresponding one of the switch members upon opposite reciprocation of the operating member and independently pivoted double lever reverse rotary motion converting toggle linkage connection with the other link for reversely effecting wiping disengagement and engagement of the other switch member with its cooperating contact during the opposite wiping operations of the one switch member.

7. A sequential switch mechanism having in combination a pair of coaxially pivoted separately operable switch members, each having an operating lever pivotally connected thereto and each having a pivotally mounted cooperating contact biased for wiping engagement and disengagement therewith, sequential operating means including a reciprocating operating member having a pivotal connection with one link for effecting wiping engagement and disengagement of the corresponding one of the switch members upon opposite reciprocation of the member, and means including a first centrally pivoted lever pivotally connected at one end with the other link to form a toggle and having a biasing spring connected to the other end of the first lever for normally extending the toggle to close the other switch member and a second centrally pivoted lever having one end provided with a cam motion connection with said other end of the toggle lever and the other end provided with a lost motion connection with the reciprocating member for collapsing the toggle to effect wiping disengagement of the other switch member during the wiping engagement of the one switch member.

8. In combination, a pivotally mounted switch member having opening and closing mechanism including a reciprocating operating member, a coaxially pivotally mounted switch member having reverse opening and closing mechanism including a lever pivoted intermediate its ends and having a lost motion connection with said reciprocating operating member at one end of the lever, a second lever pivoted intermediate its ends and having a cam motion connection between one end thereof and the other end of the first lever, a link interconnecting the other end of the

second lever with the coaxially pivotally mounted switch member to form a toggle for operating said switch to the closed position when the toggle is extended and to the open position when the toggle is collapsed, and a spring connected to bias the toggle to its set position.

9. A switch unit having in combination a pivotally mounted switch member, a reciprocating operating member therefor, a lever pivoted intermediate its ends and having a lost motion 10 sliding connection with said operating member at one end of the lever, a second lever pivoted intermediate its ends and having a cam motion sliding connection between one end thereof and the other end of the first lever, a link interconnecting the other end of the second lever with the pivoted switch member to form a toggle for operating the switch to one position when the

toggle is extended and its other position when the toggle is collapsed, and a spring connected to bias the toggle to its extended position.
